Primary Examiner — Darcey E Gottschalk(74) Attorney, Agent, or Firm — Jason T. Daniel, Esq.; Daniel Law Offices, P.A.(57) CLAIM

The ornamental design for a three compartment rolling tray, as shown and described.

DESCRIPTION

FIG. 1 is a front perspective view thereof,
 FIG. 2 is a back perspective view thereof,
 FIG. 3 is a front side elevation view thereof,
 FIG. 4 is a back side elevation view thereof,
 FIG. 5 is a left side elevation view thereof,
 FIG. 6 is a top side plan view thereof; and,
 FIG. 7 is a bottom side plan view thereof.

In the drawings, the broken lines are for the purpose of illustrating environment only and form no part of the claimed design.

1 Claim, 3 Drawing Sheets(56)
